UNITED STATES PATENT OFFICE.

ISRAEL ROSKIN, OF BROOKLYN, NEW YORK.

DESIGN FOR A SETTING FOR A FINGER-RING.

59,568.

Specification for Design.

Patented Nov. 1, 1921.

Application filed November 18, 1920. Serial No. 425,008. Term of patent 7 years.

To all whom it may concern:

Be it known that I, ISRAEL ROSKIN, a citizen of Russia, and resident of Brooklyn, in the county of Kings and State of New York, have invented a new, original, and ornamental Design for a Setting for a Finger-Ring, of which the following is a specification, reference being had to accompanying drawing, forming a part thereof, in which—

Fig 2 a top plan view of the same.

I claim:

The ornamental design for a setting for a finger ring as shown.

Signed at the city, county and State of New York this 17th day of November, 1920.

ISRAEL ROSKIN.

Witness:

E. J. ESELSTYN.
